UNITED STATES PATENT OFFICE.

JAKOB GÖHRING, OF WAINWRIGHT, ALBERTA, CANADA.

DRAWBAR.

Application filed February 19, 1926. Serial No. 89,406.

This invention relates to improvements in draw bars and the objects of the invention are to provide a durable device of this character in which the spring-actuated retaining means for the draw bar is an essential feature, being so constructed with few parts as to more satisfactorily perform the functions required of it in automatically spring actuating the draw bar.

10 Further objects are the provision of a device of this character of simplified and durable construction, more particularly adapted for use between the coaches of a train and the tender.

15 Still further objects are to provide a draw bar of this description that can be manufactured at comparatively low cost.

Further and essential objects are to provide a spring-actuated reciprocally operable 20 draw bar, particularly adapted for locomotives and cars on railroads, whereby, on the starting or stopping of a train, all "chuck" is eliminated and the operation of stopping or starting performed in a smooth even 25 manner.

With the foregoing and other objects hereinafter more fully referred to in view, the invention consists essentially in the combination with a suitable frame, of a draw 30 bar member slidably mounted therein and means formed on the draw bar adapted to automatically engage when at rest and on being moved with a plurality of spring actuating and tensioning members pivotally 35 mounted in the frame, and means for locking the draw bar.

Referring now to the drawings, in which like characters of reference indicate corresponding parts in each figure.

40 Figure 1 is a top plan view of my improved draw bar,

Figure 2 is a side elevation of the draw bar.

Figure 3 is a longitudinal section,

45 Figure 4 is a cross section on line 4—4 of Figure 3,

Figure 5 is a perspective view of the draw bar.

50 Figure 6 is a perspective view of one of the wearing guides,

Figure 7 is an enlarged section on line 7—7 of Figure 1,

Figure 8 is a perspective view of the locking member,

55 Figure 9 is a view of the underside of Figure 8,

Figure 10 is a fragmentary perspective view of the end of one of the channel plates, showing the slot and orifices therin.

Referring now more particularly to the drawings, in which a preferred example of my invention is shown in connection with a locomotive tender, 10 designates a frame, of suitable material and any suitable form, provided with a base 11 and ends 12 and 13, the sides of the frame being open.

Extending longitudinally through the base 11 is a guideway 14 registering with openings 15 and 16 in the ends. This guideway is provided with channel plates 17 formed integral with the underside of the base 11 and protruding beyond one end, as at 18, to fit beneath a locomotive tender, the sides of the protruding portion being formed on the top with flanges 19 and provided with longitudinally extending slots 20 substantially midway of their depth, the slots being designed to slidably engage with guide members 21 adapted, as at 22, to engage with the flanged edges 23 of said slots. 80 These guide members 21 are thus interchangeable and at all times renewable when worn out.

Within the guideway 14 in the base and the channel plates 17 is slidably mounted 85 the draw bar 24 designed to travel backwards and forwards therein. Adjacent one end of the draw bar are supporting guide lugs or pins 25 designed to engage with the slots 20 in the protruding end 18 of the channel plates and also to engage with the interchangeable guide members 21 slidably mounted therein. The other end of the draw bar 24 is formed with a coupling member 27, of any well known construction, to connect with the coaches of a train, while intermediate of its length the draw bar is provided with spaced lugs 28 and 29, the purpose of which is hereinafter more fully described.

100 From the foregoing it will be seen that the draw bar is slidably mounted in the base 11 on the frame 10 and that the openings 15 and 16 in the ends 12 and 13 of the frame permit the lugs 28 and 29 on the draw bar to move backwardly and forwardly through said ends with the draw bar.

Coming now to the essential feature of my invention, the means for imparting the spring-actuated reciprocal movement to the draw bar comprises pairs of finger bars 30 and 31, the members of which are pivotally

mounted, as at 32, in brackets 33, one of each pair on opposite sides of the guideway 14, and recessed at their inner ends, as at 34, to overlap, the outer ends being also 5 slightly recessed, as at 35, to engage with a vertically extending slat 36 registering with a slat or plate 37 rigidly mounted on the ends 12 and 13 of the frame and having mounted thereon on pins or lugs 38 coil 10 springs 39 and 40, the other end of said springs engaging with the slats or plates 36 carried by the finger bars 30 and 31, thus imparting a spring actuating movement to each of the pivotally mounted finger bars. 15 Intermediate of these finger bars on each side of the guideway 14 are flat plates or the like 41 and 42 formed with contact lugs 43 on each side, adapted to engage with the outer ends of the finger bars 30 and 31 to 20 limit the travel thereof in one direction. On these plates are also mounted and secured thereto tension springs 44 connected to the plates and to the outer ends of the individual finger bars, as at 35. 25 The pairs of finger bars 30 and 31 are designed to engage with the lugs 28 and 29 on the draw bar 24 and these finger bars, being pivotally mounted and spring tensioned, not only spring actuate the draw 30 bar in rest and in operation but also impart a spring-actuated reciprocal movement thereto, as when the draw bar is connected up tension thereon will be exerted in both directions, tension in one direction being 35 counteracted by one pair of spring-actuated finger bars engaging with the block 28 and tension in the other direction being counter-acted by the other pair of spring-actuated finger bars engaging with the block 40 or lug 29.

For supporting the draw bar in position and if necessary locking it within the channel plates 17 and the guideway 14, I provide slots 45 in the sides of the channel member 45 17 and also orifices 46. Into the slots 45 is adapted to fit a plate 47 bent, as at 48, at one end and provided with a slot 49 at the protruding end, into which fits a locking key 50, while intermediate of its length is a 50 riding plate 51 having formed on each side lugs 52 adapted to engage with pins 53 extending through the orifices 46 in the channel member.

To remove the draw bar when unlocked 55 the plate 47 is withdrawn, permitting the coupling end of the draw bar to drop. The interchangeable guide members 21 are then withdrawn and the draw bar moved outwardly until the supporting guide pins 25 60 disengage with the slots 20. Under ordinary

conditions it is usually unnecessary to do more than drop the draw bar, leaving the pin-carrying end pivotally supported in the slots 20.

For protecting the reciprocating mechanism as above described, I provide a cover 65 54 for the casing frame and adapted to be suitably secured thereon.

As many changes could be made in the above construction and many apparently 70 widely different embodiments of my invention, within the scope of the claims, constructed without departing from the spirit or scope thereof, it is intended that all matter contained in the accompanying specification and drawings shall be interpreted 75 in an illustrative and not in a limiting sense.

What I claim as my invention is:

1. A draw bar having spaced lugs intermediate of its length, a frame, a guideway 80 in said frame, pairs of pivotally mounted spring-actuated levers arranged, one member of each pair on each side of said guideway adapted to overlap the other and to automatically engage with the lugs on the draw bar whereby a reciprocating spring actuating movement is imparted to the draw bar.

2. A draw bar having spaced lugs thereon, levers pivotally mounted substantially 90 midway of their length and one on the opposite side of the draw bar from another and adapted to overlap each other across the bar and to engage with the lugs thereon, the other ends of the levers being spring 95 actuated in opposite directions.

3. In a device of the character described and in combination with a slidably operable draw bar having spaced lugs thereon, a pair 100 of lever arms each pivotally mounted substantially midway of their length one on each side of the draw bar, the ends of the levers being adapted to overlap across the draw bar and to engage with the lug thereon, springs at the opposite ends of said levers tending to actuate them in opposite directions whereby a reciprocal movement is imparted to the draw bar.

4. The combination, with a reciprocally mounted draw bar and a guideway adapted 110 to support said bar, of a clamping plate for the draw bar and having engaging means therein and designed to detachably engage with the guideway and to protrude therebeyond, a locking key adapted to engage with 115 said plate and an auxiliary pin extending through the plate and the guideway.

In witness whereof I have hereunto set my hand.

JAKOB GÖHRING.
